TOY

Raymond F. Harris, Brooklyn, N. Y.

Application September 25, 1942, Serial No. 459,655

6 Claims. (Cl. 46—95)

The present invention relates to toys and is more particularly directed toward a toy boat adapted for use in a container, such as a bathtub, partly filled with water.

The present invention contemplates a toy of the nature referred to wherein the toy boat is connected with the source of water under pressure by a flexible tube and the boat is provided with a rearwardly open nozzle near its stern. This nozzle is connected with the flexible tube or hose so that the water is discharged through the nozzle. This stream of water creates a reaction which propels the boat forwardly. As the boat is propelled in the container, it comes against the side walls of the container which guide it in a looplike path about the container.

The invention also contemplates the provision of a swivel which will turn so as to prevent tangling or twisting of the flexible hose.

The accompanying drawing shows, for purposes of illustrating the present invention, one of the many improvements in which the invention may take form, it being understood that the drawing is illustrative of the invention rather than limiting same.

In the drawing:

Figure 1 is a top plan view of a bathtub showing the toy boat in operation;

Figure 2 is a side elevational view of the boat and flexible tubing;

Figure 3 is a fragmentary sectional view on the line 3—3 of Figure 2;

Figure 4 is a fragmentary inverted plan view; and

Figure 5 is an enlarged sectional view showing a detail of construction.

The conventional bathtub is illustrated at 10, Figure 1, with a conventional form of plumbing connections at 11. The surface of the water is indicated at 12. A flexible hose 13 is connected at one end to the plumbing connection 11 by a rubber cup 14 such as is customarily used for a bath spray.

The other end 15 of the hose connection 13 is connected to a tube 16 and this tube is rotated connected at 17 to the end 18 of a U-shaped tube 19. This tube is suitably secured to the bottom of a boat 20 and has a nozzle 21 through which the water received through the tubing is allowed to escape.

In order that the boat may be usable as a separate toy it is contemplated that some form of quick detachable connection will be provided between the boat hull and the nozzle and hose. A convenient construction is to provide the hull 55

with a tapered undercut groove 22 and the nozzle with a slider 23 arranged to fit.

The escaping jet of water reacts on the boat and causes the boat to be propelled forwardly.

5 The boat will travel in a loop about the tub, being guided by the walls of the tub. As the boat executes the loops it will have a tendency to twist the hose. The swivel joint 17, however, is provided to avoid tangling and twisting of the hose. 10 Should this swivel joint be omitted, or the hose at any time become entangled, it can readily be untangled by merely reversing the direction of the boat's travels about the tub.

15 While the toy will ordinarily be used in a bathtub or similar container, it is, of course, possible to use it in any suitable container, provided it is substantially larger than the boat and has a corner-free contour to guide the boat. In larger sizes it may be adapted for use in an outdoor pool, for example.

20 It is obvious that the invention may be embodied in many forms and constructions within the scope of the claims and I wish it to be understood that the particular form shown is but one 25 of the many forms. Various modifications and changes being possible, I do not otherwise limit myself in any way with respect thereto.

What is claimed is:

1. In combination, a bath tub, or the like partly filled with water, a faucet connected to an outside source of water under pressure, a toy boat floating on the water, a rearwardly opening nozzle carried by the boat at the stern, and a flexible hose connection between the faucet and nozzle so that the reaction of the water discharged through the nozzle propels the boat forwardly, the tub being substantially larger than the boat and of a generally concave corner-free contour guiding the boat in a looplike path.

2. In combination, a bath tub, or the like partly filled with water, a source of water under pressure, a toy boat floating on the water, a rearwardly opening nozzle carried by the boat at the stern, and a flexible hose connection between the faucet and nozzle so that the reaction of the water discharged through the nozzle propels the boat forwardly, the tub being substantially larger than the boat and of a generally concave corner-free contour guiding the boat in a looplike path, the hose connection including swivel joint adapted to turn and prevent tangling.

3. The combination with the usual bathtub partly filled with water and a faucet connected to an outside source of water supply, of a flexible hose connected to the faucet, a toy boat small

enough to be maneuvered in the tub, and a rearwardly opening nozzle carried by the boat at the stern and connected to the hose, the boat being propellable by the reaction of the jet through the nozzle.

4. The combination of claim 3, wherein the hose connection includes a swivel joint adapted to turn and prevent tangling.

5. A toy boat adapted to float in the water in a bath tub or the like and carrying a tube having a rearwardly opening end at the stern, a swivel connected to the tube, the tube being adapted at its other end for quick detachable connection to the water faucet of the tub, whereby a jet of water may be projected rearwardly of the boat to

propel the boat forwardly, the water being discharged into the tub.

6. In combination, a toy boat adapted to float in the water in a bath tub or the like, a quick detachable tube having a rearwardly opening end below the stern of the boat, and a swivel connected to the tube, the tube being adapted at its other end for quick detachable connection to the water faucet of the tub, whereby a jet of water may be projected rearwardly of the boat to propel the boat forwardly, the water being discharged into the tub, and whereby the boat may be separated from the nozzle for use as a toy boat.
